W. S. ADAMS.

CAR TRUCK.

APPLICATION FILED APR. 6, 1915.

1,161,015.

Patented Nov. 23, 1915.

UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CAR-TRUCK.

1,161,015.

Specification of Letters Patent.

Patented Nov. 23, 1915.

Original application filed November 17, 1914, Serial No. 872,509. Divided and this application filed April 6, 1915. Serial No. 19,448.

To all whom it may concern:

Be it known that I, WALTER S. ADAMS, a citizen of the United States, and a resident of the city of Philadelphia, county of Philadelphia, and State of Pennsylvania, have invented certain new and useful Improvements in Car-Trucks, of which the following is a specification.

This application is a division of my co-pending application, Ser. No. 872,509, filed November 17th, 1914.

My invention relates to a bolster supporting means in car trucks wherein the bolster is supported near its ends on a combination of leaf and coil springs, this combination allowing the bolster to be carried true without undue jar or vibration.

The present invention also resides in certain novel features of construction and combination of elements, which will be herein-after described and further pointed out in the claims appended hereto.

For a more particular description of my invention, reference is to be had to the accompanying drawings, in which—

Figure 1 is a side elevation of my improved bolster supporting arrangement with portions of a truck being shown to illustrate its application to a truck; Fig. 2 is a front elevation of the same, partly in section; and Fig. 3 is a side elevation, partly in section, of the spring arrangement for supporting the bolster.

Throughout the various views of the drawing, similar reference characters designate similar parts.

As my invention may be applied to many kinds of trucks, I do not attempt to show any one in particular, but disclose a portion 40 of a truck which may be taken as typical of a number and I show no parts that are irrelevant to my improvements. I show portions of a frame 1, comprising top chords 2, transoms 3, gusset plates 4, bolts 5, and reinforcing plates 6, all of which may be of the conventional form.

The bolster 7 is mounted between the transoms 3, and gusset plates 4, by means of suitable bearing blocks 8, which carry spindles 9 and other parts to be described below. These bearing blocks 8 are fixed in place on the gusset plates 4 by bolts 10. Suspended from the spindles 9 are hangers 11. At the lower end of these hangers are carried spin-

gles 12, which connect the lower ends of 55 these hangers, one spindle connecting two hangers.

Each spindle 12 is made square or of like cross section at its outer ends so as to fit corresponding parts of the hangers 11 and 60 not turn therein. Between the hangers, however, the spindle 12 is made circular in cross section so as to receive and support a suitable bearing in a bracket 13, which is fixed by means of bolts 14 to a spring seat 15 65 and to angle bars 16 by rivets 17, the parts 13, 14, 15, 16 and 17 forming a spring plank. The seats 15 hold the bands 18 of lower leaf springs 19. The bolster 7 is mounted on upper leaf springs 20, held together by bands 70 21. The leaf spring 20 is bent upwardly at 23 and the leaf spring 19 downwardly at 24 in like manner. Extending between the two widened portions 25 thus formed, are the coil springs 22, carried by spring seats 26, 75 each of said seats having projections 27 fitting perforations 28 in the leaf springs.

It is to be noted that the parts 23 and 24 come together when a certain weight is imposed upon the car and then the balance of 80 the weight is carried by the leaf springs 19 and 20. It is also to be noted that when the parts 23 and 24 come together, the operative length of the leaf springs is lessened and they thus become stronger and their resistance to the weight of the load is increased.

While I have shown and described one embodiment of my invention, it is obvious that it is not restricted thereto, but is broad enough to cover all structures that come 90 within the scope of the annexed claims.

What I claim is:

1. In a truck of the class described, a truck frame, a bolster mounted in said frame, leaf springs supporting said bolster, coil springs mounted between said leaf springs and portions of said leaf springs adapted to rest together when the coil springs are sufficiently compressed.

2. In a truck of the class described, a truck frame, hangers supported by said truck frame, transversely disposed leaf springs supported by said hangers, a bolster supported by said leaf springs, coil springs mounted between said leaf springs, said leaf springs being so formed that portions of the same rest together and limit the compression of the coil springs.

3. In a truck of the class described, a truck frame, a bolster mounted in said frame, leaf springs supporting said bolster, coil springs mounted between the ends of said leaf springs, rounded portions of the leaf springs adjacent the coil springs adapted to rest together and restrict the compression of the coil springs.

4. In a truck of the class described, a truck frame, a bolster mounted in said frame, leaf springs supporting said bolster, the ends of said leaf springs being spread for the reception of coil springs, coil springs mounted between the ends of said leaf springs and portions of the leaf springs adjacent the coil springs adapted to rest together and limit the compression of the coil springs.

5. In a truck of the class described, a truck frame, a bolster mounted within said frame, leaf springs for supporting the bolster, coil springs mounted between the

leaf springs, portions formed on the leaf springs for limiting the movement of the ends of the leaf springs toward one another and shortening the operative length of the leaf springs when the parts have contacted.

6. In a truck of the class described, a truck frame, a bolster mounted in said frame, leaf springs supporting said bolster, comprising upper and lower leaf springs, coil springs mounted between the ends of said leaf springs, seats for said coil springs, projections on said seats adapted to fit perforations in the leaf springs and portions of the leaf springs adapted to contact and limit the compression of the coil springs.

Signed in the city and county of Philadelphia, and State of Pennsylvania, this 3rd day of April, 1915.

WALTER S. ADAMS.
